UNITED STATES PATENT OFFICE.

EMERY C. JEFFERSON, OF KANSAS CITY, MISSOURI.

PEN OR PENCIL HOLDER.

Application filed July 11, 1928. Serial No. 292,011.

My invention relates to improvements in pen or pencil holders.

One object of my invention is to provide a novel, simple pen or pencil holder with which a number of pens or pencils may be conveniently carried, without intermingling with each other, and without having the points of the pencils projecting above the pocket containing the holder, and without such points contacting with the pocket in a manner such as would cause holes to be made thereby in the pocket.

A further object of my invention is to provide a holder of the kind described, which is cheap, readily attachable to a pocket of a garment, and which has novel means for guiding the pencils to the positions which they are to occupy, and for embracing and supporting them in such positions in the holder.

The novel features of my invention are hereinafter fully described and claimed.

In the accompanying drawing which illustrates my invention,

Fig. 1 is an elevation of a portion of a garment the pocket of which contains one of my improved holders.

Fig. 2 is an enlarged side elevation of my improved holder with a pen and pencils mounted therein.

Fig. 3 is a further enlarged top view of the holder.

Fig. 4 is an enlarged section on the plane of the line 4—4 of Fig. 2.

Fig. 5 is a side elevation, partly broken away, of a modified form of my invention.

Fig. 6 is a section on the line 6—6 of Fig. 5.

Similar reference characters designate similar parts in the different views.

In the form shown in Figs. 1 to 4, the holder comprises a casing, which may consist of two pieces of leather 1 between which is mounted a horizontal piece of soft rubber 2, which is formed into a channel, with its doubled ends disposed between and, fastened as by stitching 3 to the two leather pieces 1, the latter, adjacent to their opposite vertical edges being fastened together by said stitching 3, Figs. 2 and 3.

The rubber channel 2 is disposed with its concave side facing upwardly, the bottom of the channel having perforations 4 adapted to receive respectively pencils 5 or fountain pens 6, Figs. 1 and 2. The channel member 2 forms within the casing a partition. It is sufficiently resilient to embrace and support

the pencils 5 and pen 6, the perforations 4 being smaller than the diameters of the pencils or pen, so that the channel member 2 is expanded by the pen or pencils inserted through the perforations 4.

The channel member 2 is disposed adjacent to the upper end of the tubular casing, and its sloping inner walls serve to guide the pencils or pen to the middle portion of the bottom of the channel, in which portion the perforations 4 are located.

The casing is adapted to be mounted in the pocket 7 of a garment 8, such as a vest. The casing is supported in an elevated position in the pocket 7 by suitable means engaging with the garment 8. Such supporting means, in the drawing, comprises two U-shaped clips 9, one set of the arms of which are disposed between one of the leather pieces 1 and the front side of the channel member 2, Fig. 3. The other arms of the clips engage the outer side of the pocket 7, Fig. 1.

In the use of the invention, the holder is slipped into the pocket 7 with the clips 9 engaging the outer wall of the pocket, as shown in Fig. 1.

The pencils 5 are then inserted points down through the perforations 4 of the channel partition member 2, which member embraces and supports the pencils with the points of the latter spaced from the bottom of the pocket, so that the points will not wear holes in the bottom of the pocket. The pen 6 and pencils 5 are firmly held, so that they are not liable to be lost out of the pocket, if the garment is inverted.

In the form of my invention shown in Figs. 5 and 6, the holder comprises a tubular casing 10, preferably consisting of a single piece of soft rubber molded to form, and having integral with the side and end walls thereof a channel portion 11 having in its bottom perforations 12 for receiving pencils 5 or a fountain pen 6, as described with reference to Figs. 1 to 4.

The casing 10 is supported by two clips 9, already described, one set of arms of which are molded in the front upper portion of the casing.

The operation is the same as was described with reference to the other form of my invention.

I do not limit my invention to the structures shown and described, as modifications, other than shown, may be made, within the

scope of the appended claims, without departing from the spirit of my invention.

What I claim is:—

1. A pen or pencil holder comprising a tubular casing adapted for insertion into a pocket and provided with a channel partition, the concave side of which faces upwardly, the partition having perforations in its bottom adapted to receive respectively therethrough 10 pens or pencils.

2. A pen or pencil holder comprising a tubular casing adapted for insertion into a pocket and provided with a resilient channel partition, the concave side of which faces upwardly, the partition having in its bottom 15 perforations adapted to receive respectively therethrough pens or pencils adapted to be embraced and supported by said partition.

3. A pen or pencil holder comprising a tubular casing adapted for insertion into a pocket of a garment and having means for 20

engagement with and for being supported in a raised position in said pocket by said garment, said casing having a channel partition, the concave side of which faces upwardly, having in its bottom perforations 25 adapted to receive respectively therethrough pens or pencils.

4. A pen or pencil holder comprising a tubular casing adapted for insertion into a pocket of a garment and having means for engagement with and for being supported in a raised position in said pocket by said garment, said casing having a resilient channel partition, the concave side of which faces 30 upwardly, having perforations in its bottom adapted to receive respectively therethrough pens or pencils adapted to be embraced and supported by said partition.

In testimony whereof I have signed my 35 name to this specification.

EMERY C. JEFFERSON.
